UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

ELECTRICAL SWITCH

Application filed June 29, 1925. Serial No. 40,327.

This invention relates to certain new and useful improvements in electrical switches and refers more particularly to that type of switch especially designed for use in connection with high current.

It is a general object of this invention to improve the construction and operation of switches designed for use with high tension current.

10 It is another object of this invention to provide an improved switch construction of the character described in which the movable contact has a slight rotational movement in the clip of the stationary contact prior to a 15 breaking movement to thus permit the ready freeing of the contacts and prevent any tendency of the parts to freeze.

Another object of this invention resides in the provision of an improved stationary 20 spring clip which is simple to manufacture and which will afford maximum electrical engagement with the movable contact.

25 And a still further object of this invention resides in the provision of an improved means for easing the movement of the contacting mechanism to either of its limits and thus prevent the banging or jarring of the parts.

With the above and other objects in view 30 which will appear as the description proceeds, my invention resides in the novel construction, combination and arrangement of parts substantially as hereinafter described and more particularly defined by the 35 appended claims, it being understood that such changes in the precise embodiment of the hereindisclosed invention may be made as come within the scope of the claims.

In the accompanying drawings, I have 40 illustrated one complete example of the physical embodiment of my invention constructed according to the best mode I have so far devised for the practical application of the principles thereof, and in which:

45 Figure 1 is a side view of a switch unit embodying my invention, parts being broken away and in section;

Figure 2 is a sectional view of a movable contact and mechanism for actuating the same, said view being taken through Figure 1

on the plane of the line 2—2, parts thereof being broken away and in section;

Figure 3 is a view partly in section and partly in elevation taken through the stationary contact on the plane of the line 3—3 of Figure 1, and

Figure 4 is a detail sectional view of the movable switch blade, said view being taken through Figure 2 on the plane of the line 4—4.

Referring now more particularly to the accompanying drawings in which like numerals designate like parts throughout the several views, the numeral 5 designates a transverse beam or support of the customary frame work upon which switches of this character are mounted, the beam 5 bridging standards or other members 6. The switch may be arranged in units of one or more and when used as a three phase switch in connection with an oil switch, three units are employed, although but one is shown in the drawings.

Fixed to the beam 5 adjacent one end is a bracket support 7 which has a flanged surface 8 inclined inwardly to receive the flanged base 9 of an insulator support 10 which is bolted thereto, as at 11, the support 10 mounting a suitable petticoat or other type of insulator 12 on the outer end of which a stationary contact 13 is fixed. The stationary contact 13 includes an approximately Y-shaped bracket member 14, the leg or vertical portion 15 of which forms a contact proper and the arms 16 and 17 of which provide means for the mounting of the contact on the insulator and the supporting of the adjacent end of the line or conductor 18.

The arm 16 is flanged at its end and secured to the top of the insulator 12 and also is flanged along one edge, as at 19, and has one end of an arcing horn 20 adjustably secured thereto by a clamping plate 21. The outer end of the arm 17 is enlarged, as at 22, and formed with a V 23 in which the conductor 18 rests and is clamped by a plate 24, the inner end of the conductor being electrically connected to a terminal 25 which is electrically connected with a contact clip or blade member 26 by bolts 27 which also serve to secure the clip or plate 26 to the leg of the

Y 14. The clamping arrangement provided by the V 23 and plate 24 relieves the connection between the line 18 and the terminal 25 of all mechanical strains and also provides an emergency source for carrying a good portion of the current in case of a faulty joint between the line and the terminal as the current, in such event, will pass from the line at the clamp and through the bracket member to the contact blade.

The outer end of the Y member is offset parallel with respect to the clip 26 and has a recessed portion or pocket 27 in which the guide stud 28 of a yieldable or floating clip 29 is mounted, a spring 30 being concealed in the recess and coiled about the stud to normally urge the member 29 outward of member 26, the outer ends of said members being flared or curved laterally, as at 31, to facilitate the entrance therebetween of the movable contact blade 32.

The movable contact blade 32 is mounted on an insulator 33 of petticoat or any other suitable construction by a pair of spaced standards, lugs or ears 34 formed on a flange 35 which is suitably secured to the insulator 33.

The blade 32 is mounted between the lugs 34 by a pivot bolt 36 and a second bolt 37, the opening 38 in the spring blade through which the bolt 37 passes being of increased diameter permits a limited swinging movement of the switch blade for the purpose later described. The flange 35 is grooved, as at 39, 35 to receive the inner end of an arcing horn 40 which is adjustably secured therein by a clamping plate 41 and which extends upwardly to cooperate with the arcing horn 20 of the stationary contact. The horn 40, like 40 the horn 20, being adjustable permits their ready setting to vary the contact or tension therebetween, as will be obvious.

The insulator 33 is mounted on a support 42 somewhat similar to the support 10 which 45 is fixed to a bracket 43 mounted on a rotatable shaft 44 journaled in bearings 45 carried by the beam 5. The shaft 44 is rotated by a crank arm 46 fixed thereto and to the end of which an operating rod 47 is connected, 50 the other end of the rod 47 being connected with a suitable actuating mechanism, not shown. Limit screws 45 define the travel of the shaft and are threaded in lugs 46 formed on the bearing 45. The screws 45 engage the bracket 43 at either of its limits 55 of movement as best shown in Figure 1.

The switch blade 32 is connected with the line 48 through a ribbon conductor 49, one end of which is clamped between the parts 60 50 of a terminal 51 riveted or otherwise electrically connected with the blade 32, as at 52, and having its other end clamped between the part 53 and a mounting 54 of a terminal 55 to which the line 48 is connected. In this manner the line is directly connected with the

switch blade 32 and any possibility of trouble, such as would be encountered were a friction joint relied on to carry current, is eliminated. The support 54 is mounted on the top of an insulator 56 which is of petticoat or other suitable type and is carried by a mounting 57 bolted or otherwise secured, as at 58, to the transverse member 5 on the side of the shaft 44 opposite the stationary contact.

The insulator 56 and its support takes the 75 train of the line 48 which is clamped thereto in a manner similar to the connecting of the line 18 to the bracket 14, and the ribbon 49 is loose to free the movable contact of any strain and is guarded against coming in contact with the parts of the switch by the toggle link arrangement best illustrated in Figure 1.

The flange 35 and the support 54 have their adjacent ends provided with apertured lugs 59 to which the outer ends of levers 60 and 61 are connected by pivots 62 and 63, respectively, the inner ends of the levers being pivotally connected by a pin 63'. Each lever 60 and 61 is formed of a pair of links held in spaced relation by the apertured lugs 59 and by suitable bushings, not shown, mounted on the pivot pin 63' and the ribbon 49 passes from the terminal 55 over a bolt 64 medially connecting the links of the levers 61, under the pivot 63' and over a bolt 65 medially connecting the links of the levers 60 so that with the contact blade 32 in circuit closing position, the ribbon 49 is in a substantially straight line from the terminal 55 to the terminal 51.

The levers 60 and 61 are of a length so that their pivot 63' never falls below an imaginary line drawn through the pivots 62 and 63 so that movement of the insulator mounting carrying the switch blade, is not interfered with, as is best illustrated in Figure 1. As the insulator mounting for the switch blade 32 is swung therewith, to the right with reference to Figure 1, breaking the continuity of the current from one line to the other, the levers 60 and 61 assume the dotted line positions illustrated and the ribbon 49 is supported from touching the supporting structure or the insulator parts of the switch by the bolts 64 and 65. The inner ends of the terminal parts to which the ends of the ribbon 49 are connected, are preferably flared or curved, as at 66, to protect the ribbon as it is bent in the opening and closing of the switch.

A plurality of the switch units are generally controlled from a single rod 44 and the mechanism being of considerable weight causes a considerable jar to the device as it is moved to either of its limits and I provide an improved means for easing or absorbing the shocks incidental to the coming to rest of the movable parts to thus prevent possible injury to the mechanism. I accomplish this result by coiling a spring 67 about the shaft 44 ad- 130

5 Jacent the transverse member 5 with its ends 68 and 69 disposed on opposite sides of a lug or projection 70 extended from the side of the transverse member 5 and on opposite sides of the instruck or lateral arm 71 of a crank 72 fixed to the shaft 44 adjacent the spring, as at 73. As will be evident, when the switch mechanism is moved to closed position, the end 68 of the spring presses against the pro-
 10 jection 70 and the end 69 is moved with the arm 71 of the crank 72 as a result of which the tension of the spring increases as the switch approaches closed position. A move-
 15 ment of the switch mechanism in an opposite direction to open the switch, causes the arm 71 to move the switch arm 68 with it, the switch end 69 bearing against the projection 70 and the tension of the spring increasing as the mechanism approaches its dotted line 20 position illustrated in Figure 1 to thus ease the shock of the mechanism coming to rest.
 25 Switches of the character illustrated are kept closed for indefinite periods of time, as a result of which the contacts tend to freeze, making it difficult to actuate the parts to break the circuit without some injury to the mechanism. This objectionable feature is overcome by the novel manner of mounting the switch blade 32 which is permitted a limited pivotal movement by reason of the opening 38 being of a greater diameter than the bolt 37 passed therethrough or else being of elongated nature. With the switch closed, the switch blade is moved to the right its full
 30 35 limit with reference to Figure 1 by reason of the weight of the mechanism bearing thereagainst so that upon opening movement the switch blade is given a slight rotational movement in the spring contact 31 as will be ap-
 40 parent, thus breaking the contact 32 free of the members 31 in the event they have frozen to permit the free continued movement of the mechanism to disengage the contact 32 from between the members 31.
 45 From the foregoing description taken in connection with the accompanying drawings, it will be readily apparent to those skilled in the art to which an invention of this character appertains that I provide an
 50 55 improved switch construction which will eliminate injury to the parts due to the coming to rest of the movable mechanism with a considerable force, which will permit the ready opening of the switch without injury in the event the switch contacts have become frozen and one in which an improved type of spring clip is employed to insure maximum electrical contact with the movable switch blade.

60 What I claim as my invention is:

1. In a switch construction, a contact clip comprising a member having its outer end cut away to provide a laterally and then longitudinally directed arm, a floating contact
 65 clip member extended parallel with respect

to the arm and spaced therefrom, a second contact clip member fixed to said member and extended over the arm, the outer end of said second contact clip member and the other contact clip member forming the contactor clip, and a spring confined between the arm and first contact clip member and urging said first-mentioned contact clip member toward the other clip member. 73

2. In a switch construction, a contact member comprising a conductor support of approximately Y-shape, means on one arm of the Y facilitating its mounting on a support, means on the other end of the Y to which the end of a conductor line may be connected, the outer end of the leg of the Y being offset laterally and then longitudinally, a contact clip secured to the leg of the Y and extended over the offset end thereof, a second contact clip mounted between the extended end of the first clip and the offset portion of the Y leg, and means resiliently urging the second clip toward the extended end portion of the first clip. 75 80 85

3. In a switch construction, a pair of spaced stationary insulators, one of said insulators being inclined upwardly and inwardly toward the other, a movable insulator mounted between the first mentioned insulators, a contact clip carried by the inclined insulator, a switch blade, means mounting the switch blade on the movable insulator whereby the blade has a degree of unrestricted pivotal movement with respect to its mounting, means for actuating the movable insulator 90 95 100 to engage and disengage the blade with the contact clip, means connecting the contact clip carried by the inclined insulator with a line, means connecting a second line with the other stationary insulator, and means electrically connecting the second line with the switch blade, said line securing means rigidly connecting the lines with their associated insulators. 105

4. In a switch construction, a movable contact, a stationary contact adapted to be engaged with the movable contact and including a bracket member having an offset portion, a contact clip fixed to the bracket member and overlying the offset portion, a floating contact clip positioned between the offset portion and the fixed clip, and means yieldably urging said floating clip towards the fixed clip whereby the floating clip is free to retain a position parallel with the fixed clip 110 115 120 after the engagement of the movable contact therewith between the clips.

5. An electric switch contact, comprising a bracket, an arm extended therefrom, a contact clip fixed to the bracket and overlying the arm but spaced therefrom, a second contact clip, cooperating means carried by the second contact clip and the arm for floatingly retaining the second contact clip between the arm and the fixed contact clip and means 125 130

yieldably urging the second contact clip towards the first, whereby the second contact clip is at all times free to assume a position parallel with the first contact clip.

6. In a switch construction, a pair of contacts adapted to be engaged with each other, one of said contacts including a member having an extended end portion, a contact clip carried by the member and overlying said extended end portion but spaced therefrom, a floating contact clip positioned in the space between the extended end portion and the first-mentioned contact clip, and means yieldably urging said floating contact clip toward the other contact clip whereby the clips are free to maintain a position parallel with each other.

In testimony whereof I affix my signature.
ALWIN G. STEINMAYER.
